SPLITTING MACHINE

Harry Lyon, Holbrook, Mass., assignor to United Shoe Machinery Corporation, Paterson, N. J., a corporation of New Jersey

Application April 12, 1934, Serial No. 720,279

9 Claims. (Cl. 69—11)

This invention relates to splitting machines and is herein illustrated as embodied in a machine for removing a thin shaving or split of uniform thickness from the grain side of a leather sole or insole.

5 In the manufacture of boots and shoes, for example in the preparation of insoles for welt shoes, it is customary to remove a thin shaving or split from the grain side of each insole to make the insoles more flexible and to prevent 10 them from cracking during wear of the shoe in which they are to be incorporated. It is also customary in some cases to remove a thin grain split from the tread faces of outsoles before they are incorporated in shoes instead of buffing said 15 tread faces after the soles have been attached to the bottoms of shoes, a machine for performing these operations being disclosed in United States Letters Patent No. 1,260,436, granted March 26, 1918, upon an application filed February 12, 1915, 20 in the name of Thomas J. O'Keeffe.

In the patented machine a sole, insole or other pieces of leather is fed over a table and past a stationary knife by a yielding roll the axis of which is parallel to the cutting edge of the knife, 25 the thickness of the split which is removed being determined by the distance between a plane passed longitudinally of the knife through the edge thereof and the plane of the work-supporting face of the table over which the work is fed. The 30 split or shaving which is removed is usually a very thin and flimsy one so that the splitting operation must be very accurately performed. In order to improve the operation of machines for removing thin splits or shavings from sheet material, the 35 present invention provides a construction in which the work is fed beneath a presser or gage to a knife by a turntable having a deformable work-supporting portion.

40 In the illustrated construction the flat-faced work-supporting portion of the turntable is made of rubber so as to provide for pieces of work which are not of uniform thickness throughout, and the edge of the knife is disposed at an angle to the radii of the turntable so that a draw cut is produced.

45 These and other features of the invention including certain details of construction and combinations of parts will be described as embodied in an illustrated machine and pointed out in the 50 appended claims.

Referring to the accompanying drawings,

Fig. 1 is a front elevation of a machine in which the present invention is embodied;

55 Fig. 2 is an end elevation of the machine with certain parts broken away; and

Fig. 3 is a plan of a portion of the machine showing a sole in process of being operated upon.

The frame 5 has integral with it two alined half-bearings 7, 9 in which are received respectively the trunnions 11, 13 of a knife and gage carrier 15, said carrier being held in adjusted angular position about the axis of its trunnions by clamping caps 17, 19 which are fastened respectively to the half-bearings 7, 9 by cap screws 21. A knife 23 is adjustably fastened on an inclined plate or flange 25 of the carrier 15 by bolts 27, said bolts passing through holes in the knife and through slots in the flange. The knife may thus be adjusted in an inclined path after the bolts 27 have been loosened, and may be adjusted 15 angularly by loosening the cap screws 21 and swinging the carrier 15 about the axis of its trunnions 11, 13.

Slidable in an undercut guideway in the carrier 15 is a work presser or gage 29, the lower 20 portion of which is rounded as indicated at 29' (Fig. 2) so that the effective portion of the gage is a thin edge located slightly above the edge of the knife. It is the distance of the gage 29 above the edge of the knife 23 which determines 25 the thickness of the shaving or split removed from a piece of work. The gage 29 may be adjusted to vary this distance by turning a screw 31 which is threaded into the upper part of the gage 29 and is held from longitudinal movement 30 by collars 33 rigid with the stem of the screw and engaging respectively the upper and the lower faces of a bar 35 fastened to the carrier 15 by cap screws 37.

The work is fed beneath the thin lower edge 35 of the gage 29 to the knife 23 by a flat-faced turntable 39, the work-supporting portion of which is deformable, being herein shown as a flat annular rubber member mounted in an annular recess in the frame of the turntable. The 40 turntable is fastened to the upper end of a vertical spindle 43. Formed on the lower side of the turntable is a hub 45 between which and the head of a threaded sleeve 47 are a series of balls 49 to provide a ball thrust bearing for supporting 45 the turntable, holes 51 being provided in the head of the sleeve for the insertion of a rod by the use of which the sleeve, which is threaded into the frame 5, may be turned to raise or lower the turntable. The vertical spindle 43 is rotatable in 50 this sleeve and in an alined bore below it formed in the frame 5. Formed on the lower portion of the turntable is a large gear 53 which meshes with a pinion 55 on the upper end of a vertical shaft 57 rotatable in a bearing in the frame of 55

the machine, the lower end of the vertical shaft 57 having fast to it a bevel gear 59. A bevel pinion 61, fast to one end of a horizontal shaft 63, meshes with the bevel gear 59. The other end 5 of the shaft 63 carries a pulley 65 which may be rotated by a belt, not shown, from any suitable source of power.

In the use of the machine the knife is adjusted into the desired angular position by loosening the cap screws 21 and swinging the carrier 15 about the axis of its trunnions so that there will be proper clearance for the passage of the work between the knife and the turntable. The gage 29 is adjusted by turning the screw 31 until the 10 distance between its lower thin extremity and the edge of the knife is equal to the desired thickness of the split or shaving which is to be removed; and the turntable is adjusted to the proper height by turning the sleeve 47. Power is then applied 15 to rotate the turntable continuously. The operator stands in front of the machine and places soles one after another upon the rubber top of the turntable, whereupon they are carried successively to and past the knife. By referring to 20 Fig. 3, it will be seen that the edge of the knife is disposed at an angle to the radii of the turntable and that the knife is thus caused to operate 25 upon a sole 100 or other piece of work with a draw cut.

30 Although the invention has been set forth as embodied in a particular machine, it should be understood that the invention is not limited in the scope of its application to the particular machine which has been shown and described.

35 Having thus described my invention, what I claim as new and desire to secure by Letters Patent of the United States is:

1. A splitting machine having in combination, 40 an unyielding gage, a knife having its cutting edge closely adjacent to but spaced somewhat from the edge of the gage, a turntable including a deformable portion upon which the work is placed, and means for rotating the turntable to feed the work past said knife and gage.

45 2. A splitting machine having in combination, 45 an unyielding gage, a knife having its cutting edge closely adjacent to the gage, a turntable including a deformable portion upon which the work is placed, said turntable being adjustable toward and from the gage, and means for rotating the turntable to feed the work past the knife and gage.

50 3. A splitting machine having in combination, 55 an unyielding gage, a knife having its cutting edge closely adjacent to but spaced somewhat from the edge of the gage, a turntable including a deformable portion upon which the work is placed, and means for rotating the turntable to feed the work past said knife and gage, said deformable portion yielding to accommodate variations in the thickness of the work whereby a thin shaving of uniform thickness passes between the gage and the knife and is removed from each

piece of work irrespective of variations in its thickness.

4. A splitting machine having in combination, 5 an unyielding gage, a knife having its cutting edge closely adjacent to but spaced somewhat from the edge of the gage, a turntable including a deformable portion upon which the work is placed, and means for rotating the turntable to feed the work past said knife and gage, said deformable portion yielding to accommodate variations in the thickness of the work whereby a thin shaving of uniform thickness passes between the gage and the knife and is removed from each 10 piece of work irrespective of variations in its thickness, the edge of the knife being arranged 15 at an angle to the radii of the turntable so that a draw cut is produced upon the work.

5. A splitting machine having in combination, 20 an unyielding gage, a knife having its cutting edge closely adjacent to but spaced somewhat from the edge of the gage, a substantially flat-faced turntable including a deformable work-receiving portion, and means for rotating the turntable to feed the work past said knife and gage, 25 said knife and gage being relatively adjustable to vary the space between them.

6. A splitting machine having in combination, 30 an unyielding gage, a knife having its cutting edge closely adjacent to but spaced somewhat from the edge of the gage, a substantially flat-faced turntable including a deformable work-receiving portion, and means for rotating the turntable to feed the work past said knife and gage, 35 said knife being adjustable to vary its angular relation to the plane of the surface of the turntable.

7. A splitting machine having in combination, 40 a base, a turntable rotatably mounted thereon, a carrier pivotally mounted on the base and extending over the turntable whereby said carrier may be adjusted angularly, a knife mounted on the carrier and a gage having its work-engaging portion in front of the edge of the knife and located above the level of that of the edge of the knife.

8. A splitting machine having in combination, 45 a base, a turntable rotatably mounted thereon, a carrier pivotally mounted on the base and extending over the turntable whereby said carrier may be adjusted angularly, a knife adjustably 50 mounted on the carrier and a gage having its work-engaging portion in front of the edge of the knife and located above the level of that of the edge of the knife.

9. A splitting machine having in combination, 55 a base, a turntable rotatably mounted thereon, a carrier pivotally mounted on the base and extending over the turntable whereby said carrier may be adjusted angularly, a knife mounted on the carrier and a gage also mounted on the carrier and having its work-engaging portion in front of the edge of the knife and located above the level of that of the edge of the knife.

HARRY LYON.
